MAGNETIC SEPARATOR

Roswell H. Stearns, Wauwatosa, Wis., assignor to
 Stearns Magnetic Mfg. Co., Milwaukee, Wis., a
 corporation of Wisconsin

Application August 30, 1944, Serial No. 551,802

1 Claim. (Cl. 209—225)

1

This invention relates to magnetic separators which are primarily designed for the refining and recovery of low grade iron ores.

It is a well known fact that supplies of the rich ores in America of the hematite variety have been greatly depleted and are being rapidly further reduced to such an extent that it is now necessary to resort to the separation and concentration of the low grade magnetite ores and those commonly known as magnetic taconite. It is also a well known fact that deposits of low grade ores, such as set forth above for instance, are large and abundant in this country and are conveniently located for handling and shipping, but heretofore great difficulty was encountered in efficiently and cheaply separating and concentrating such low grade ores. Most of these low grade ores contain clay matter and other impurities which must be eliminated by washing and scrubbing while under the influence of a magnetic field.

Objects of this invention are to provide a magnetic separator which will efficiently and cheaply separate and concentrate low grade ores, and which is so constructed that it has means for thoroughly washing and scrubbing the ores while subjected to a blanket like magnetic field so as to quickly and effectively free the ore from the gangue to thus secure a rich, free, iron concentrate and obtain a very high recovery of such ore with a minimum waste in the tailing product.

Further objects are to provide a simple and effective means of feeding the mixture in a thin and uniformly spread sheet into a primary magnetic field against the face of a travelling belt so that the magnetically responsive ore is attracted and held against the belt while the non-magnetic portions of the mixture drop out as worthless tailings, the construction being such that the belt travels across the faces of a multitude of magnet poles in intimate contact with such poles while the belt is passing through a blanket like magnetic field.

Further objects are to provide a separator having an electromagnet structure of the alternate pole type in which there are alternate rows of magnet poles transversely of the belt with the poles provided with elongated fingers extending longitudinally of the belt and arranged in spaced intermeshed or staggered relation to thus spread the magnetic lines of force over a large area and thereby produce a blanket like magnetic field, thus maintaining the ore in a uniform thin sheet and creating a highly agitating effect,

2

rolling the ore completely over and over and causing a zig-zag movement crosswise of the moving belt, thus not only producing a beneficial scrubbing action which removes the silicious coating on the ore but also freeing the ore from other matter such as the entrained gangue matter and bonded inclusions of iron and gangue as a middlings product.

Further objects are to provide a separator in which the ore is carried in suspension while fresh clean water is caused to wash and impinge against the suspended ore, the water travelling in a direction counter to that of the belt thus carrying any floating gangue matter away from the concentrate discharge end of the machine, the water becoming cleaner and cleaner as the concentrate discharge end of the machine is approached so that the final concentrates are washed in substantially clean water.

Further objects are to provide an electromagnetic separator in which means are provided for protecting the magnets and the windings thereof from the water used in the cleaning, washing and scrubbing of the ore, and to so construct the separator that only the belt and the projecting poles of the electromagnets dip into the water.

In greater detail, further objects are to provide an electromagnetic separator in which the electromagnet windings are housed between an upper and a lower jacket with the poles extending below the lower jacket and with the upper jacket provided with downturned marginal flanges overhanging and spaced from upturned marginal flanges on the lower jacket, and to provide means for forcing clean, fresh air around the magnet windings and discharging the air through the space between the marginal flanges of the upper and lower jackets to thus remove any moisture that may form due to condensation or sweating of the parts.

Further objects are to provide a magnetic separator provided with a plurality of rows of sprays which may be independently adjusted for different zones in the separator, which will spread the water into a uniform sheet and project it against the travelling belt, in which the pressure or head of water is indicated for each row of sprays, in which a high pressure feed spray is employed to assist in the feeding of the material to the separator, and in which means are provided for spreading the material uniformly on the under side of the travelling belt.

An embodiment of the invention is shown in the accompanying drawings, in which:

Figure 1 is a longitudinal sectional view

55

through the separator with some of the parts broken away and some of the parts shown in full.

Figure 2 is a side elevation of the separator with parts broken away.

Figure 3 is a sectional view on the line 3—3 of Figure 1.

Figure 4 is a sectional view on the line 4—4 of Figure 1.

Figure 5 is a fragmentary sectional view showing one of the overflow portions.

Figure 6 is a view looking upwardly towards the pole pieces.

Figure 7 is a sectional view on the line 7—7 of Figure 6.

The separator comprises a plurality of electromagnets indicated generally by the reference character 1 and consisting of cores 2 surrounded by energizing windings 3 and attached at their upper ends to longitudinally extending yoke or top members 4 and provided at their lower ends with pole pieces 5. The electromagnets are located within a housing or casing 6 formed of non-magnetic metal and terminating in an upper marginal edge 7. The casing is completed by an upper portion 8 which is provided with a downwardly extending marginal edge portion 9 overhanging the edge portion 7 and spaced therefrom.

The construction of electromagnet is shown in greater detail in Figure 7. The yoke members 4 consist of magnetic rectangular bars which are secured to the cores 2 by means of bolts 10, see Figure 7. The pole pieces 5 are secured to the under side of the cores 2 by means of screws 11. The pole pieces are formed of magnetic material and are spaced a slight distance from the cores 2 by means of the non-magnetic casing 6, the screws 11 passing through the casing and clamping the casing tightly between the cores 2 and the neck portions 12 of the pole pieces 5. These neck portions are each provided with forwardly and rearwardly projecting portions constituting pole pieces. The pole pieces are arranged in transverse rows and the pole pieces of adjacent rows are arranged in staggered relation to each other, as shown in Figure 6. The pole pieces 5, as will be seen particularly from Figure 6, are elongated both towards the feed end and the delivery end of the machine and are approximately narrow, oval-shaped members formed integrally with the neck portions 12. The pole pieces of one row intermesh with the pole pieces of adjacent rows, as shown in Figure 6, so as to produce a multiplicity of strong magnetic fields.

A pair of wooden guide strips 13 are located on the under side of the casing 6 and on opposite sides of the pole pieces. These wooden marginal strips form bearing rails for the side edges of a rubber or composition non-magnetic belt 14. The belt 14 is a continuous belt and passes below the pole pieces 5 and bears on their smooth under faces and also bears on the guide rails or marginal wooden strips 13. Preferably the lower portion of the magnet assembly is slightly bowed downwardly to accommodate approximately the catenary shape that the belt assumes.

At the feed end of the machine a transverse guiding wooden member or bar 15 is provided and has a rounded bottom guiding surface for the belt 14. A guide roller 16 is positioned immediately adjacent the guide member 15. At the delivery end of the belt the wooden guiding rails as well as the magnet assembly are curved upwardly, as shown in Figure 1. The belt passes over a driving pulley 17 adjacent the concentrate

delivery end of the machine and over an adjustable idler roller 18 adjacent the feed or inlet portion of the separator. The driving roller 17 is driven in any suitable manner as from the motor 19.

It is to be noted that the upper portion 8 of the housing is so formed as to provide a series of transverse compartments 20, 21 and 22 each supplied with circulating air through the air manifold or supply pipe 23, such manifold or supply pipe being fed from a blower 24 driven by a motor 25, see Figure 3.

It will be seen that air is blown into the space between the upper and lower portions 8 and 6 of the casing and serves to cool the coils of the electromagnet and also to prevent moisture from collecting on the electromagnets or other portions within the casings 6 and 8. The air is discharged between the marginal portions 7 and 9 of the lower and upper casings and thus it will be seen that the electromagnet coils are kept thoroughly dried and well ventilated by the means hereinabove described.

The separator is adapted to effect separation while the material is being passed through water and while it is being sprayed. For this purpose a tank or water containing trough like member 26, see Figure 1, is provided and extends from the feed end of the machine to the concentrate delivery end thereof. This trough like member is formed so as to provide a tailings hopper 27 and also a middlings hopper 28 adapted to respectively receive the tailings and middlings, as will be described hereinafter. For convenience each of the hoppers may be formed in two portions, as shown most clearly in Figure 3. Each of the hoppers is provided with outlet or discharge valves 29 which may be opened at periodic intervals or may remain partially or fully opened at all times.

A dewatering section 30 is provided adjacent the concentrate delivery end of the machine and a concentrate receiving hopper 31 is provided at a point beyond the dewatering section 30. A pair of box like overflow or discharge members indicated by the reference character 32 are provided adjacent the feed end of the machine, as shown in Figure 2. One of the overflow portions 32 is shown in section in Figure 5. The marginal edge of the trough like member 26 is cut down at each of the discharge portions 32, as shown in Figure 5, to maintain the water level at the line indicated by the reference character 33 in Figure 5.

The material is fed by any suitable means, not shown, into a feed hopper 34, see Figure 1, and passes down the feed chute 35 and is delivered through the upturned portion of the feed chute through a slot 36 extending transversely across the belt and beneath the belt. A spreading table or feed distributing member 37 is provided and a transverse blocking strip 38 is located rearwardly or towards the feed end of the machine and spaced slightly from the delivery slot 36, as shown in Figure 1, to prevent material from spreading rearwardly. The spreading table 37 constitutes a plateau for providing a very thin film of material uniformly spread whereby substantially only magnetic material is picked directly upwardly against the under side of the belt and entangling of nonmagnetic material is reduced to a minimum. The forward travel of the belt as indicated by the arrows in Figure 1 removes the material from the spreading plate or feed portion 37 so that the material is carried 75 from the feed portion of the device in a uniform

and evenly spread layer on the under side of the belt.

In order to facilitate the feeding of the material a feed spray pipe 38 extends transversely across the machine beneath the feed chute 35 and has a series of small spray openings opening into the feed chute 35 to assist in the feeding of the material and also to assist in uniformly distributing the material. The inner end of the feed chute 35 is supported by means of adjustable tie bolts 35'. These bolts may be adjusted to vary the spacing between the spreading table 37 and the belt 14 to thus vary the feed. The feed chute 35 is sufficiently springy to accommodate the relatively slight movement occasioned by this adjustment.

The tailings or non-magnetic material falls into the tailings hopper 21. It is preferable to have the electromagnets adjacent the feed end of the machine strongest and the electromagnets at the delivery end of the machine weakest, the magnets located adjacent the middle portion of the separator being of intermediate strength. Means, not shown, are provided for controlling the amount of current supplied the electromagnets to thereby control their relative strengths. By having the strongest magnetic effect over the tailings hopper, all of the magnetic material, both the strongly magnetic and the faintly magnetic, is held against the under side of the belt over the tailings hopper. However over the middlings hopper the magnetic effect is less than the faintly magnetic material or middlings therefore fall from the belt into the middlings hopper. The concentrates still cling to the belt even though the belt passes through a less and less intense magnetic zone as it approaches the delivery end of the separator so that the material finally delivered from the belt when it passes beyond the influence of the magnets is a high grade concentrate. It is to be distinctly understood, however, that the magnets, if desired, may all be of the same intensity or other arrangements of relative intensity from that described hereinabove may be obtained without departing from the spirit of this invention.

The magnetic material including the highly magnetic and the faintly magnetic material is held against the under side of the travelling belt and is carried through the liquid bath. The material clinging to the under side of the belt is sprayed by means of a plurality of transversely extending spray pipes 39 provided with spray openings directed upwardly and provided with angularly adjustable baffle or guiding members 40 so as to spread the individual streams from the openings into a thin, uniform sheet of water which is projected against the belt in a direction contrary to that of the travel of the belt. The baffles also act as guards to protect the openings in the pipes from falling material.

Each of the groups of sprays is individually adjusted by means of inlet valves 41 which are interposed between the respective groups of sprays and the supply manifold 42. Also the feed spray may be adjusted by means of the hand valve 43, see Figure 2. It is to be noted that each transversely extending spray pipe 39 is connected to a gauge 44, as shown in Figure 2, which gauge consists of an open-ended glass or other transparent tube so as to indicate the head or pressure at which the sprays are supplied. It has been found that by having the group of sprays close to the feed end of the machine of greatest velocity and the magnets adjacent such end of greatest

strength that the best results are obtained, the velocity of the sprays being less and less as the feed end of the machine is approached. Any other relative pressures or heads could be maintained on the sprays as desired.

It is to be noted also that the drift or travel of the water adjacent the belt is in a direction opposite to that of the travel of the belt and floating particles are thus caused to travel towards the discharge or overflow portions 32 so that such floating particles will be discharged from the machine in a continuous manner.

The non-magnetic tailings fall into the hopper 27 and the middlings fall into the hopper 28 as the strength of the magnets adjacent the hopper 28 is less than the strength of the magnets adjacent the hopper 27. Some water is carried over into the dewatering section 30 and falls from the belt into such section and is discharged from the machine. The concentrates cling to the belt until the last magnet poles are passed and at such point the concentrates fall into the concentrate hopper or discharge hopper 31, see Figure 1. The middlings, if they are of no particular value, may be discarded or if the material is such that the middlings have a reasonable amount of magnetic material therein, they may be reground and again passed through the machine either alone or mixed with fresh material.

It is to be noted particularly with reference to the arrangement of sprays in Figure 1 and the arrangement of magnet poles in Figure 6 that while the material is being sprayed it is bounding and zigzagging and turning over and over as it passes from a row of magnet poles of one polarity to the next adjacent row of poles of the opposite polarity. The material is caused to zigzag or shift laterally of the belt by means of the staggered intermeshing relation of the pole pieces, as shown in Figure 6, and it is obvious that as the material passes from a pole piece of one polarity to a pole piece of another polarity that there is a tumbling or turning action in addition to the zigzag shifting action of the material. This rapid changing of position of the particles while in the magnetic field not only produces a beneficial scrubbing action which removes the silicious coating from the ore, but it also frees from entrainment other gangue matter and bonded inclusions of iron and gangue as a middlings product. The sprays are so arranged that they act on the material at the points of greatest agitation and thus additionally assist in the separating action.

It has been found that the separator provides a high value concentrate and that the tailings are substantially free from any magnetic particles. It has also been found that the machine will separate at one passage of the material therethrough the tailings, the middlings and the concentrates.

It will be seen also that the material is spread over the under surface of the belt at the feed end by means of the spreading table or small platform 37 and by means of the feed spray 38' in a thin and uniform layer completely across the belt. Also it is to be noted that the magnetic field is of considerable width and extends from adjacent one side of the belt to adjacent the other side thereof and throughout the active length of the belt.

By having the wooden guide rails 13, see Figure 3, and the transverse wooden guide member 15 and by having a relatively extensively exposed flat face provided by the faces of the pole pieces 5, see Figure 6, the belt is not subjected to much wear but travels smoothly over these several flat faces.

Also with a rubber belt or a composition belt it has been found that water acts as an excellent lubricant for the belt and thus as the belt is wet while the machine is in operation there is very little friction between the belt and the portions against which it bears during its travel.

It is to be noted also that by means of the construction hereinabove set forth and illustrated in the drawings there is no chance of the material getting in between the belt and the pole pieces and thus scoring of the pole pieces and cutting of the belt is avoided.

The water gauges for each of the sets of sprays allows the operator to ascertain at a glance the exact head or pressure of water supplied the different groups of sprays so that he may set the sprays individually to the exact requirements for the particular material being treated by the separator. Also it is to be noted that there is a general drift of water towards the feed end of the machine and thus the muddy or dirtiest water is driven towards the feed end of the machine and discharged through the discharge means, the mud or other tailings collecting in the tailing compartment. By this means final washing of the material takes place in clean water.

It is to be noted also that not only is the material passed through a water bath during separation but the material is also highly agitated during its passage through the water bath and in addition is subjected to the action of individually controlled sprays at the zones where the material is most highly agitated. Thus the non-magnetic material held by the clinging magnetic material is freely shaken and washed from the magnetic material and a very high degree of separation is thus secured. If desired, spray means, not shown, may be provided to assist in removing the concentrates from the belt.

It is to be noted that the electromagnets are protected from the water and that moisture is prevented from forming on the electromagnets due to the air stream that is forced through the electromagnet assembly, such air stream also cooling the electromagnets.

Another feature that is to be noted particularly is that the material is fed directly against the lower side of the belt at the feed end of the machine and directly beneath powerful electromagnets and the material, therefore, is not allowed to drop away from the belt while it is being fed to the belt but is spread thereon in a uniform and thin layer by the spreading platform. This causes all of the material to be subjected to an intense magnetic field at the beginning of the separating process so that all magnetic material

will be held securely against the under side of the belt at the beginning of its travel through the separator and thus there will be practically no loss of magnetic material with the tailings.

Although this invention has been described in considerable detail, it is to be understood that such description is intended as illustrative rather than limiting, as the invention may be variously embodied and is to be interpreted as claimed.

10 I claim:

A magnetic separator comprising a liquid containing tank, an endless belt having a lower stretch passing through the liquid in said tank, means for driving said belt, feed means at one end of said separator for feeding material to the under side of said belt, a plurality of magnets having rows of pole pieces extending transversely across said belt, said rows of pole pieces being spaced lengthwise of said belt and being of opposite polarity and having portions intermeshing with and spaced from portions of adjacent rows to provide a zone of changing polarity to produce zones of greatest agitation for magnetic material clinging to the under side of said belt, spray means 15 directed towards said belt to produce circulation of the liquid adjacent the zones of greatest agitation, said spray means including pipes extending transversely across said tank and having upwardly directed spaced spray openings and slanting baffles overhanging said spray openings and protecting said spray openings from falling material and serving to spread and direct a thin, substantially uniform sheet of water against the under side of said belt, said belt having a discharge portion at a point beyond said pole pieces, 20 and means for receiving concentrates from the discharge portion of said belt.

ROSWELL H. STEARNS.
